UNITED STATES PATENT OFFICE.

JOSEPH H. DALTON, OF ST. PAUL, MINNESOTA.

SAND CUTTING AND SCREENING MACHINE.

1,227,589.

Specification of Letters Patent. Patented May 29, 1917.

Application filed October 13, 1916. Serial No. 125,374.

To all whom it may concern:

Be it known that I, JOSEPH H. DALTON, a citizen of the United States, residing at St. Paul, in the county of Ramsey and State of Minnesota, have invented a new and useful Improvement in Sand Cutting and Screening Machines, of which the following is a specification.

This invention relates to an improvement 10 in sand cutting and screening machines, and more particularly to a machine designed to be used on the molder's floor in the foundries and factories.

The object of this invention is to provide 15 a portable machine for cutting and screening the molding sand by passing the machine over the floor on which the sand is left after having been used in molding.

With this invention a good deal of manual 20 labor can be saved, as the machine can be operated easily and quickly over the molding floor by one man, and the sand will be more thoroughly mixed and also cleaned of burned cores, scrap and other undesirable 25 material which becomes mixed with the sand while molding.

It is an object of this machine to have a revolving riddle or screen which is open on both ends and has a cone shaped deflector, 30 centrally disposed on the axis thereof in the same.

A further object is in a machine which is self propelled and the riddle can be left 35 out of operation when desired while moving the machine from place to place.

Other features of this invention will be more fully described in the following specification and claims.

In the accompanying drawings which 40 form part of this specification:

Figure 1, is a side elevation of the machine.

Fig. 2, is a top or plan view of the machine.

Figs. 3, 4, 5 and 6 are details of various 45 parts of the machine.

Fig. 7, is a diagrammatic view of the sand elevator, illustrating the raised and lowered position of the same.

In the drawing A represents an angle 50 iron frame which is supported by forward wheels 1 and rear wheels 2. The rear wheels 2 are slightly larger than the forward wheels, and are adapted to propel the frame over the molding floor, and are preferably formed with a roughened sur-

face or shoes which are adapted to grip on the floor while driving the machine. The front wheels are adapted to guide the course which the frame takes over the floor when 60 being operated. The wheels 1 are secured to a vertical shaft 6 which is freely journaled at the front of the frame A, so that the wheels can be turned by the steering rod 3 which is connected by a rack and gear or 65 in any suitable way to a steering wheel 4 on one end, and to the arm 5 on the forward end. The arm 5 being rigidly secured to the journal shaft 6 of one of the front wheels 70. A tie rod 7 connects the two front wheels 70 together in the usual way.

A riddle B is mounted on the frame A and is cylindrical in shape, being formed with any desired mesh of screening and open on both ends. The riddle being 75 mounted with its axis on an angle with the frame A and rigidly secured to the shaft 8, which is positioned on the axis of the riddle. The forward end of the riddle is freely carried in the semi-circumferential 80 bearing 9, which is rigidly secured to the frame A by the arm 10.

The semi-circumferential bearing 9 is formed with a channel 60 in which the forward outer end of the riddle B is adapted 85 to rotate. The channel 60 having a depressed portion 61 in which rollers or ball bearings 62 are adapted to rest, so that the circumference of the riddle B will roll or bear on the rollers 62, thereby, reducing 90 the friction on the bearing 9.

A cone shaped deflector C is centrally disposed in the riddle B and on the axis thereof, the apex of the cone being secured to the end of the shaft 8. Braces 11 are 95 secured to the forward end of the deflector C and to the inner circumference of the riddle B to hold the deflector rigid in operation of the riddle.

The shaft 8 is formed in two parts, 25 100 and 26, which are held in axial alinement with the riddle B by the bearings 12. The motor D is adapted to drive the shaft 8 through the gear 13 and the angle gear 14, the gear 13 being rigidly mounted on the motor shaft 15, and the gear 14 being rigidly secured to the portion 26 of the shaft.

A clutch 16 is interposed between the portions 25 and 26 of the shaft 8, the clutch being of the ordinary tooth construction, and 110 adapted to be operated by the handle 16'. Thus, the riddle B can be thrown into or out

of operation by means of the clutch 16 during the operation of the motor D. The rear wheels 2 are adapted to be propelled by the motor D, by means of the gears 13 and 14, 5 and bevel gear 17 on the end of the shaft 8 meshing with the bevel gear 18, which is mounted upon the transverse shaft 19 and gear 20 mounted on the shaft 19 meshing with gear 21, which is mounted upon the 10 transverse shaft 22. Shaft 22 being connected by means of sprockets and chain 23 with the rear wheels 2. Thus, it is evident that when it is desired to drive the machine or frame A by turning on a switch which is 15 not illustrated, the machine can be propelled over the molding floor. It is obvious that the motor can be so arranged as to operate in either direction, and thus, operate the machine forward or backward as desired, 20 and that any suitable motive power, such as gasolene engine, etc., can be used to take the place of the motor D.

An elevator E is carried by the forward end of the frame A by frames F and G. 25 The frames F and G being rigidly secured to the frame A. The elevator E being composed of an endless belt 27, which is a trifle narrower than the diameter of the riddle B, and carries a series of cups 28, the cups 28 being practically the same length as the width of the carrier belt 27. The upper end of the belt 27 is carried by the roller 29, which is mounted upon the shaft 30, and the lower end of the belt passes over the roller 31 which is carried by the transverse shaft 32. Bellcrank arms 33 which are pivotally connected to the frame F at 34 are adapted to hold the shaft 32 in the positions illustrated in Figs. 1 and 7.

40 The bellcrank arm 33 on one side is pivotally connected at 35 to the operating rod 36, and the other end of the rod 36 is pivotally connected at 37 to the lever 38, which is pivoted to the frame A at 39, and has a handle 40 on its opposite free end by which the lever 38 can be engaged to operate it back and forth on the quadrant 41, which is of ordinary construction.

45 The lever 38 is equipped with an ordinary locking dog 42 which engages in the notches 43 in the quadrant. Thus, when the lever 38 is placed in the forward position as is illustrated in Fig. 1, the elevator E is placed in operating position, so as to have the cups 28 pass in close proximity to the floor upon which the machine is operating. Arms 44 are pivotally connected to the bellcrank levers 33 at 45 on one end, and the other end freely engaging a lug 46, which is rigidly connected to the frame F. Thus, when the lower end of the elevator E is dropped into the position illustrated in Fig. 1, the arms 44 will limit the forward movement of the bell crank arm 33, and also assist in holding 60 the lower end of the elevator rigid while

the machine is in operation and being propelled forward.

When it is desired to raise the lower end of the elevator E the lever 38 is pulled into the backward position, raising the lower 70 end of the elevator E as is illustrated in Fig. 7. The free ends of the arms 44 sliding backward on the frame F.

The elevator E is adapted to be operated by the motor D through the shafts 15, 48 75 and 49. The shafts 48 and 49 being driven by bevel gears which connect the shafts 48 and 49 with the driving shaft 15. The bevel gears being inclosed in protecting housings 50. The shaft 49 extends longitudinally 80 with the frame A to the forward end of the frame; and has a pulley 51 secured to the forward end of the same over which a belt 52 is adapted to pass. The belt 52 is crossed in the usual manner as illustrated in Fig. 1 85 and passes over pulley 53 which is secured to the transverse shaft 30 at the upper end of the elevator E. Thus, it is evident that when operating the machine the motor D will drive the elevator E through the shafts 90 15, 48 and 49 and by means of the belt 52.

A tooth clutch 54 is interposed between the two parts of the shaft 15 and is of the ordinary construction, as is illustrated in Figs. 5 and 6, being also similar to the 95 clutch 16. Thus, when it is desired the elevator can be thrown in or out of operation by means of the clutch 54. It is obvious that the elevator E may be driven in any other suitable way from the source of motor 100 power, such as the motor D, and that in place of the belt 52, a chain may be used which is also true of the belt 27, it being evident that link chains may be used to hold the cups 28 and carry the same up to the 105 elevator.

In operation the sand cutting machine is propelled over the molding floor with the lower end of the elevator E raised as illustrated in Fig. 7, and out of operation. The riddle B also being out of operation until the machine has been brought up to where the molding sand is located on the molding floor. Then by means of the lever 38 the lower end of the elevator E is dropped into the position illustrated in Fig. 2, and the clutches 16 and 54 closed so as to operate the riddle B and the elevator E. As the machine travels forward it will scoop up the sand with the cups 28 and carry it up and 115 deposit it into the forward end of the riddle. If the elevator E is run at a high enough rate of speed it will tend to throw the sand into the riddle striking the deflector C and sliding out of the same onto the 120 mesh of the riddle B.

The loose free clean sand passing downward through the mesh of the riddle and onto the molding floor directly under the frame A. The burnt cores, scrap and other 125 130

undesirable material will slide along the lower surface of the riddle to the rear of the same, and be deposited into a receptacle 55. The receptacle 55 extending transversely across the frame A, and being secured thereto. Deflectors 58 are secured to the lower part of the frame A just below the riddle B, which tend to deposit the same passing through the riddle centrally below the machine.

The operator of the machine steers the same by means of the handle 4 from place to place over the molding floor. With this machine it is thus possible to thoroughly mix and clean the molding sand on the molding floor after it has been used in casting or in molding, and leave it in a neat and compacted shape ready to be used for molding again. This machine will do away with the hard labor of hand mixing the sand, and when it is mixed by hand, it is pretty hard to thoroughly clean the same. Thus, by the use of this machine the life of the sand will be lengthened and the castings obtained from the same will average very much better. As the elevator E is so arranged that the sand elevating cups run in close proximity to the floor, practically all of the same will pass through the machine when the machine passes over the sand in operation.

As the sand is carried by the elevator E into the riddle B, it is thoroughly agitated and sieved in passing through the riddle and any particles too large to pass through the screen of the riddle are carried back into the receptacle 55.

While I have illustrated one form of construction and combination of parts, I desire to have it understood that this is only illustrative, and that my invention can be carried out by other means and applied to other uses within the scope of the following claims.

45. What I claim is:

1. A self propelled sand cutting and screening machine comprising, a supporting frame, a rotatable riddle carried by said frame, wheels for carrying said frame, means for holding said riddle with the area of its sand receiving end free of any obstructions, a deflector axially held in the rear of said riddle and an elevator adapted to feed sand into the receiving end of said riddle when said screening machine is operated, substantially as described.

2. In a self propelled sand cutting and screening machine, comprising, a supporting frame, a riddle rotatably mounted upon said frame, wheels by which the frame is

carried, an elevator frame mounted on the forward end of said supporting frame to hold the elevator in close proximity to the floor over which the machine is passed, said riddle being axially supported by a shaft 65 which extends a short distance into said riddle, a deflector secured to the end of said shaft and held axially in the end of said riddle so that when sand is elevated by said elevator and deposited in said deflector it will 70 freely slide out of said deflector to the surface of said riddle, thereby preventing the sand from passing through said riddle without being screened.

3. In a device of the class described having a supporting frame, wheels for carrying said frame, a screen mounted on said frame adapted to screen sand deposited therein, a sand conducting elevator having its upper end immovably mounted on said frame adjacent the receiving end of said screen, and means pivoted on said frame for raising or lowering the lower end of said elevator, substantially as described.

4. In a self propelled sand cutting and screening machine adapted for use on a molder's floor, comprising, a supporting frame driving wheels by which said frame is carried, a riddle mounted to be rotatable on said frame, an elevator to conduct the material being treated from the floor and feed it to said riddle, said riddle being open on both ends and mounted to a driving shaft on one end, with its receiving end completely open and clear of any obstructions so as to 95 freely receive the material from said elevator, a receptacle extending across said frame directly below the rear end of said riddle so that the waste material only will fall directly from the rear end of said riddle 100 into said receptacle and means for operating said riddle and for propelling said machine.

5. A self propelled sand cutting and screening machine comprising a supporting frame, a rotatable riddle carried by said 105 frame, wheels on which said frame is mounted, a conical deflector axially supported by its apex in said riddle, said deflector and riddle having an open receiving end free of any obstructions, an elevator to conduct sand from the floor and feed it into said deflector, means for simultaneously operating said riddle and elevator while said machine is being propelled whereby sand is deposited into said deflector by said conductor and is 110 free to be spread from the surface of said deflector to the surface of said riddle, substantially as described.

JOSEPH H. DALTON.
